BLAST FREEZER

Herman W. Kleist, Chicago, Ill., assignor to Dole
Refrigerating Company, Chicago, Ill., a corpora-
tion of Illinois

Application June 28, 1948, Serial No. 35,546

4 Claims. (Cl. 62—102)

1

My invention relates to an improvement in refrigerating devices, and has for one purpose to provide a freezer for freezing food and other substances.

Another purpose is to provide a cabinet in which articles may be frozen, and, when frozen, may, if desired, be stored.

Another purpose is to provide an improved freezing and storage assembly which may be employed to chill or refrigerate a surrounding space, such as a storage room.

Another purpose is to provide a so-called blast freezer in which a current of air is circulated across the goods being stored or frozen.

Other purposes will appear from time to time in the course of the specification and claims.

I illustrate my invention more or less diagrammatically in the accompanying drawings wherein:

Figure 1 is a vertical section;

Figure 2 is a perspective view, on an enlarged scale, illustrating a storage and freezing unit;

Figure 3 is a detail through an individual cooling element; and

Figure 4 is a cycle diagram, diagrammatically illustrating a mechanical refrigerating assembly which includes refrigerating plates in the cabinet illustrated in Figure 2.

Like parts are indicated by like symbols throughout the specification and drawings.

Referring to the drawings, I generally indicate the wall or walls of a storage space or room, the floor being indicated at 2 and the ceiling or roof at 3. It will be understood that, if desired, the room or space may be suitably insulated, and the members 1, 2 and 3 will be understood to indicate suitably insulated members. 4 diagrammatically indicates a door or entrance normally kept cold.

Within the space defined and surrounded by the insulating walls, floor and ceiling, 1, 2 and 3, I illustrate a cabinet which may include a bottom member 5, a back wall 6, side walls 7, a front wall portion 8, and a top wall 9. It may be desirable to insulate the cabinet walls, and I illustrate the wall structures 5, 6, 7, 8 and 9 as double wall constructions, with an insulating filler 10. Doors 11 are hung in suitable door apertures 12, formed in the front wall 8. It will be noted, however, that each door 11 terminates at its lower edge, as at 13, substantially above the level of the floor. Thus an air inlet is provided beneath each door 11. The top wall 9 is broken by one or more hoods 14, each of which may be provided with any suitable air circulating fan 15 and louvres

2

16. It will thus be understood that when the fan 15 is rotating, air is drawn inwardly beneath the lower edges 13 of the doors 11, and is outwardly expelled through the hoods 14 and between the louvres 16.

Within the cabinet I illustrate a shelf assembly, each shelf of which is formed by a refrigerating plate which is part of the mechanical cooling system diagrammatically shown in Figure 4. 10 Considering, first, the plates, I illustrate plane faced plates having sheet metal horizontal walls 17 and 18 connected by circumferential flanges or walls 19, and enclosing a space in which is an evaporating coil 20. Any suitable means may be 15 formed for holding the walls 17 and 18 in proper heat exchange relationship with the coil 20. I may, for example, partially exhaust the interior of each plate through a suitable fitting 21, which, when the air within the plate has been partially 20 exhausted, may be sealed. As a result of this pressure differential the pressure of the atmosphere is effective to thrust the wall members 17 and 18 toward each other and against the coil 20. Refrigerating plates of the type above described, 25 since they are plane surfaced, constitute satisfactory shelf units. Since each such shelf includes an evaporating coil, each shelf serves as a refrigerating element.

I find that the freezing time of goods put in 30 the cabinet for freezing is reduced by maintaining a flow of air through the cabinet. The air is initially cooled by the lower plates illustrated as 22 and 23, which are located below the lower edge 13 of the door 11. Additional plates are 35 arranged in staggered relationship. I may, for example, provide plates 24 and 25, which engage or extend to the rear wall 6 of the cabinet. I illustrate other plates 26 and 27 which engage either the front wall or the closed door 11. In the space between these directing baffles I position additional plates 28 which are free at each edge, and about which and between which air may flow in response to the action of the fan 15, in the direction of the arrows in Figure 1.

45 With reference to the refrigerating cycle, I may use any suitable means for causing evaporation of a volatile refrigerant in the coils 20. It will be understood that each of the above described plates has a coil, such as is shown in Figure 3. For convenience, the coils of the various plates may be arranged in series, as shown in Figure 4.

With reference to Figure 4, 30 is a motor which, through the belt 31, drives the compressor 32. 33 is a suction line, extending from the

plate coils to the compressor 32. 34 is a pressure line extending from the compressor 32 to any suitable condenser structure 35. 36 is a collector, and 37 is a high pressure liquid line extending to any suitable pressure reduction valve or means 38. The drop in pressure caused by the member 38 is effective to cause the volatile refrigerant to evaporate in the coils 20, with the desired refrigerating effect.

It will be realized that, whereas, I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

The use and operation of the invention are as follows:

I provide a simple, compact and efficient unit which may be employed to freeze foods and other substances. Under certain circumstances, it may be useful as a storage cabinet. It may also be used to maintain a relatively low temperature in a room or space in which the cabinet is positioned.

It will be observed that, with reference to Figure 1, when the unit is used in a room, cooled air is directed across the top of the room beneath the ceiling 3 and tends to displace the warmer air which rises upwardly in the room, mixing it with the cool air. Air is inwardly drawn along the floor in the direction of the arrows, for recirculation through the staggered sets of shelves constituted by the cold plates.

I claim:

1. In a cooling cabinet adapted for the simultaneous cooling of articles within the cabinet and of air exterior to the cabinet, walls defining a refrigeration space and an access opening thereto, a door movably closing said access opening, a plurality of shelves arranged in said space in staggered relation, said shelves being refrigerating plates having evaporators associated therewith, means for cycling a volatile refrigerant through the evaporators of said plates, said cabinet having an air inlet and an air outlet and means for circulating air from without said cabinet through said inlet, through the refrigerating space within the cabinet and through said outlet, said shelves being positioned between said inlet and outlet and defining with the walls and closure a tortuous refrigerating passage, said door when closed only partly filling said access opening, thereby leaving a portion of the access opening unobstructed for use as an air inlet to or air outlet from the refrigeration space within the cabinet.

2. In a cooling cabinet adapted for the simultaneous cooling of articles within the cabinet and of air exterior to the cabinet, walls defining a refrigeration space and an access opening thereto, a door movably closing said access opening, a plurality of baffle shelves arranged in said space in staggered relation, said shelves being refrigerating plates having evaporators associated therewith, means for cycling a volatile refrigerant through the evaporators of said plates, said cabinet having an air inlet and an air outlet and means for circulating air from without said cabinet through said inlet, through the refrigerating space within the cabinet and through said outlet, said baffle shelves being positioned between said inlet and outlet and defining with the walls and closure a tortuous refrigerating passage, said door when closed only partly filling said access opening, thereby leaving a portion of the access opening unobstructed for use as an air inlet to or air outlet from the refrigeration space within the cabinet.

erant through the evaporators of said plates, said cabinet having an air inlet and an air outlet and means for circulating air from without said cabinet through said inlet, through the refrigerating space within the cabinet and through said outlet, said baffle shelves being positioned between said inlet and outlet, and a plurality of vertically spaced groups of intermediate shelves mounted within the cabinet, with one pair only of the opposite edges of each such shelf out of contact with the cabinet, the out-of-contact edges of the intermediate shelves being generally vertically aligned, said baffle shelves being disposed respectively between successive groups of intermediate shelves, the baffle shelves each having one edge only out of contact with the cabinet, said out-of-contact edges of the baffle shelves being disposed alternately at opposite ends of successive shelves and respectively in general vertical alignment with the out-of-contact edges of the intermediate shelves of the groups disposed immediately above and below the same, whereby the baffle shelves define with the cabinet walls and said closure a tortuous refrigerating passage through which the air passes in a plurality of parallel paths between the shelves of each group and in opposite directions through the shelves of successive groups.

3. In a cooling cabinet adapted for the simultaneous cooling of articles within the cabinet and of air exterior to the cabinet, walls defining a refrigeration space and an access opening thereto, a door movably closing said access opening, a plurality of shelves arranged in said space in staggered relation, said shelves being refrigerating plates having evaporators associated therewith, means for cycling a volatile refrigerant through the evaporators of said plates, said cabinet having an air inlet and an air outlet and means for circulating air from without said cabinet through said inlet, through the refrigerating space within the cabinet and through said outlet, said shelves being positioned between said inlet and outlet and defining with the walls and closure a tortuous refrigerating passage, said air inlet to the cabinet being constituted by a portion of the access opening located below the door, the door being shorter than said access opening.

4. The structure described in claim 3 wherein the air outlet opening is in the top of the cabinet, a tubular deflector casing surrounding said outlet opening, and wherein the means for circulating the air comprises a blower disposed within said deflector casing.
